UNITED STATES PATENT OFFICE.

FRANK H. BICKFORD, OF MUNCIE, INDIANA, ASSIGNOR TO THE ADDER MACHINE COMPANY, OF WILKES-BARRE, PENNSYLVANIA, A CORPORATION OF PENNSYLVANIA.

PRINTING MECHANISM.

1,112,516.

Specification of Letters Patent.

Patented Oct. 6, 1914.

Application filed October 21, 1911. Serial No. 656,066.

To all whom it may concern:

Be it known that I, FRANK H. BICKFORD, a citizen of the United States, residing at Muncie, Delaware county, Indiana, have 5 invented new and useful Improvements in Printing Mechanisms, of which the following is a specification.

This invention relates to improvements in printing mechanisms, adapted to those 10 machines wherein a type is brought opposite the printing line and is then caused to print by a blow from a striker.

The device constitutes an improvement on the mechanism disclosed in United States 15 patent to Wales 940,758, dated November 28, 1909, wherein a series of slotted plungers located intermediate the hammers and the type carriers are pivotally supported on a bar passing through the slots. Springs connected to the respective plungers and to a 20 rod in the frame normally retain the plungers retracted, and a stop bar extends over the rear or striking ends of the plungers to arrest the upward swing of the latter. 25 One object of this invention is to provide a stronger, simpler and less expensive means whereby to communicate the impact of the hammers to the types.

A further object is to provide means tending 30 to prevent what is known as "ghosting," which results from a deviation of the plunger out of its normal path, whereby it contacts with two type stems causing the imprint of parts of two characters above or 35 below the printing line. This improvement also tends to prevent lateral or vertical displacement of the plungers which would permit them to glance off of the type stems.

In the accompanying drawings, Figure 1 40 is a vertical section through a printing mechanism of the well-known Wales calculating machine, parts being shown in dotted lines. Fig. 2 is a broken plan. Fig. 3 is a longitudinal section through the plunger mount. Fig. 4 is a perspective thereof.

Although the invention is illustrated as applied to a Wales calculating machine, its use is not confined thereto.

Fig. 1 discloses a single type carrier with 50 its coöoperating mechanisms, it being understood that this is but one of several such mechanisms arranged side by side in the machine, as partially illustrated in Fig. 2.

The type carriers comprising heads 3 55 have their stocks L² slidably mounted be-

tween guides 1 secured to the frame 2. Spring-retracted type stems L³ are slidably mounted in the heads 3 of the carriers, types 4 being secured on the rear ends of the stems to strike through a ribbon 5 against a 60 platen M.

Bent levers L, (one only being shown), pivoted on a rod 6, are connected to the respective type carriers by links L¹ and rocked in the usual manner to shift the carriers 65 relatively to the platen, to bring the desired types opposite the printing line. The strokes of said levers may be controlled by the springs H and bars B, as explained in Patent No. 940,758.

Rests P⁴ on trip bars P² are pressed against the arms L⁵ of the levers L by springs P³. The trip bars pass between guides 7, and as the levers L rock in the direction of the arrow (Fig. 1), when positioning the types relatively to the printing line, they free the trip bars P² to the action of their springs P³, which cause the bars to contact dogs or latches P normally occupying notches 8 in the hammers L⁴, to displace said latches. The hammers are journaled on a shaft N and a detent O common to all the hammers and fast on a shaft O² journaled in the frame, normally holds the 75 hammers retracted or cocked. There are as 80 many latches and trip bars as there are hammers, said latches operating to lock the hammers individually, so that unless the latches are tripped, the hammers controlled thereby are held idle when released by the 85 detent O, and no type impressions are made 90 on the paper.

Each latch P may have a tail P⁶ to trip the next latch to the right, to effect the 95 printing of ciphers as is well understood in the art.

Springs N¹ connected to the respective hammers by slotted shackles 9 and to cranks N² on a rock-shaft 10, drive the hammers on their effective strokes. A stop rod 11 100 passes through the slots 24 in the several shackles, which latter are connected to the hammers by pins 12 passing through openings 13 in the several hammers, of greater 105 diameter than the pins.

During the initial stroke of the lever L, an angle lever N⁵, shown in dotted lines Fig. 1, fast on shaft N is turned by any suitable mechanism (not shown) to rock shaft 10 through link N⁴ and arm N³, thereby 110

turning the crank N^2 to tension the drive springs N^1 of the hammers L^4 . The angle lever N^5 being fast on the shaft N also rocks said shaft to withdraw a restoring bar O^6 5 from in front of the hammers, said bar being connected to the shaft N by arms 14. As the angle lever nears the end of its initial stroke, it brings one end of a slot 15 in a link O^4 , against the free end of an arm O^3 10 fast on the shaft O^2 to rock the latter to displace the detent O against the tension of its locking spring 16 and release such of the hammers as have been freed from the latches P , to the action of their tensioned 15 springs N^1 .

Owing to the idle preliminary travel of the link O^4 due to the slot 15, the hammers are not released until after the types have been positioned relatively to the platen, and 20 the type carriers brought to rest.

The foregoing construction is old and only constitutes part of the present invention, insofar as it is combined with the new parts now to be set forth.

25 Several plungers 17 are interposed between the hammers and the type stems L^3 , said plungers being arranged side by side and in line with the forward ends of the type stems when the latter have been 30 brought to printing position, to transmit the force of the hammer blows to the types. In the present instance, said plungers are supported in a mount or bed comprising a pair of guide bars or members 18 spaced 35 apart from each other and apertured to receive the plungers, which rest near their opposite ends in said guides, said opposite ends projecting beyond the respective guides. Preferably, the plungers are 40 straight and cylindrical to fit into round apertures 19 in the guides. Said apertures in one guide, in the present instance, are aligned with the respective apertures in the remaining guide. Each plunger may have 45 a shoulder or stop 20 against which one end of a spring 21 bears to normally hold the plungers in retracted position, said spring encircling the plunger. The guides 50 18 are secured to end plates 22 fastened to the frame 2 and a brace 23 connects the end plates to afford strength and rigidity.

The hammers whose latches P have been disengaged therefrom, when released by the 55 detent O , are driven by their springs N^1 against the forward ends of the plungers to forcibly project the opposite ends thereof against those type stems 23 which are positioned for printing.

60 The length of the slots 24 in the shackles 9 is such as to arrest the action of springs N^1 just prior to the contact of the types with the platen, but the hammers continue on their effective strokes under acquired impetus, due to the play between the pins 12 65 and the walls of the openings 13 in the

hammers. The shock of arrest of the type stems and types by the platen is transmitted through the plungers to the hammers to cause the latter to rebound whereupon the springs 25 and 21 restore the type stems and plungers respectively, to their normal positions.

The return strokes of the levers L restore the type carriers and the types to their positions of rest and the return stroke of the angle lever N^5 rocks the shaft 10 and the cranks N^2 thereon to release the tension on the drive springs N^1 . Also said lever N^5 rocks the shaft N and restoring bar O^6 to retract or cock the hammers. The hammers 80 ride under the spring-pressed detent O as they return to retracted position, and when the hammers clear the detent, the latter snaps over the hammers, under the tension of its spring 16, to hold them retracted, 85 such operation of the detent being permitted by the slot 15 in link O^4 which link has been returned toward normal position by the lever N^5 . The levers L on their return to normal position, press against the rests 90 P^4 on the trip bars P^2 to withdraw the trips from contact with their latches P , so that when the hammers L^4 are cocked, said latches are snapped into locking engagement therewith by their springs 26. 95

It will be observed that the plunger section is self contained, inexpensive to manufacture, and may be readily applied to and removed from the frame. It is also strong and durable and the spaced guides tend to 100 prevent other than a direct backward and forward thrust of the plungers toward and from the type stems, whereby to prevent contact of the plungers with other than the type stems aligned with the printing line, and 105 to prevent the plungers from glancing off said stems.

What I claim as new, is—

1. In a printing mechanism, the combination with a frame; a series of type-carrying 110 members; and a series of printing hammers therefor; of a self-contained plunger mechanism interposed as an entirety between the type-carrying members and the printing hammers, and fixed to the frame. 115

2. In a printing mechanism, the combination with a frame; a series of type-carrying members; and a series of printing hammers therefor; of a self-contained plunger mechanism interposed as an entirety between the 120 type-carrying members and the printing hammers; and comprising a series of plungers; and a combined guiding and supporting means in which said plungers are shiftably mounted, said guiding and supporting means being fixed to the frame. 125

3. In a printing mechanism, the combination with a frame; a series of type-carrying members; and a series of printing hammers therefor; of a self-contained plunger mech- 130

anism interposed as an entirety between the type-carrying members and the printing hammers; and comprising a pair of apertured guiding and supporting plates; and a 5 series of plungers seated in the apertures, the ends of said plungers extending beyond the outer faces of the plates.

4. In a printing mechanism, the combination with a frame; a series of type-carrying members; and a series of printing hammers therefor; of a self-contained plunger mechanism interposed as an entirety between the type-carrying members and the printing hammers; and comprising a series of 15 plungers; a combined guiding and supporting means in which said plungers are shiftably seated; and springs coiled about the plungers and bearing against the guiding means and plungers, respectively.

20 5. In a printing mechanism, the combination with a series of type carriers adjustable relatively to the printing line; several type bars mounted for back and forth movement in the respective carriers and having 25 types thereon; a hammer for each type carrier, and means to trip the hammers, of a self-contained plunger mount interposed, as an entirety between the type bars and ham-

mers, said mount comprising end plates secured to the frame of the mechanism, and a 30 pair of apertured, oppositely disposed guides extending between the end plates; and spring pressed plungers, the opposite ends of which project through the apertures in the guides and lie in the paths of said 35 hammers and opposite said types, respectively.

6. In a printing mechanism, the combination with a printing hammer, and printing type, of apertured guide members 18 interposed between the hammer and the stem of the type, a plunger 17 seated in the apertures, with its forward end in the path of the hammer and its rear end lying opposite the type stem when the latter is in printing 40 position; said guide members constituting the sides of a plunger box, having ends 22 and a brace 23; a coiled spring 21 encircling the plunger and bearing against a stop thereon to restore the plunger to normal 45 position.

FRANK H. BICKFORD.

In the presence of—

EDWARD W. SWAN,
DANIEL C. SPENCER.
